United States Patent Office

Des. 192,015
Patented Jan. 2, 1962

192,015

PLATE OR SIMILAR ARTICLE

John H. Reiser, Downey, Calif., assignor to Wallace China
Co., Ltd., Los Angeles, Calif., a corporation of Cali-
fornia

Filed Aug. 7, 1961, Ser. No. 66,223

Term of patent 14 years

(Cl. D44—15)

The figure is a plan view of a plate or similar article, of conventional configuration, showing my new design.

The motif shown is repeated around the circumference of the plate.

I claim:

The ornamental design for a plate or similar article, substantially as shown and described.
